FLOOR SURFACING MACHINE

Jean Alder, Zurich, Switzerland

Application November 30, 1931, Serial No. 578,071
In Germany December 6, 1930

2 Claims. (Cl. 15—93)

The present invention relates to a machine for scraping and polishing floors.

Various types of motor-driven floor scraping and polishing machines are known already, in which rotating rollers or discs or reciprocating plates are provided with steel shavings. The former suffer from the drawback that the cutting angle of the steel shavings never varies and the shavings do not alter their relative position, so that the spaces between the shavings are rapidly filled up with the waste produced during the dressing of the floor and the output of the machine is thus considerably reduced, and the latter require considerable pressure, owing to the large surface applied to the floor, which causes compression of the steel shavings with the result that the interstices will quickly fill up with waste particles and the efficiency of the outfit will be lowered also.

20 The invention provides a floor scraping and polishing machine, in which two rocker members symmetrically disposed on horizontal parallel shafts are arranged whose lower portions are adapted to receive steel shavings and brushes and which are swung to and fro about the shafts by means of two connecting rods arranged on crank pins staggered 180° and positioned on a driving shaft located between the rocker members.

25 In the machine according to the invention the steel shavings do not move on the surface to be dressed but on two cylindrical surfaces, and only a strip of both rocker members will touch the floor at a given time. The pressure to be exerted need therefore not be so great as if the entire surface were in contact with the floor as in some of the known outfits.

Furthermore, compared with the known types, the machine according to the invention provides 30 for a reciprocating motion of the steel shavings on the two cylindrical surfaces, the shavings being slightly displaced relative to one another at each reversal of motion so as to cause scrapings and the like to drop out and keep the shavings always unhampered thereby. Moreover, owing to the rotary motion of the rocker members, the cutting angle of the steel shavings will be altered, so that it becomes possible to work almost 35 completely the corners between two walls, which cannot be done with other machine employing, for example, rotary plates. The symmetrical arrangement of the two rocker members neutralizes the displacing action, and the machine in operation will therefore disclose only a slight,

periodic, vertical motion which helps to shake waste particles out of the steel shavings.

The machine according to the invention is preferably combined with a vacuum cleaner and a device for waxing floors.

One form of the invention is illustrated in the accompanying drawing, in which

Figure 1 is a side view thereof, partly in section, on the line I—I, of Fig. 2;

Fig. 2, a cross section on the line II—II, of Fig. 1;

Fig. 3, a section on the line III—III, of Fig. 2;

Fig. 4 is a longitudinal section of the steel wool holder; and

Fig. 5 is a cross section thereof on a larger scale.

Referring to the drawing: On a jacket 1 resting on the floor with bristles disposed on its lower edges the electric motor 2 having a vertical shaft is arranged. Inside the jacket 1 a casing 3 is provided in which the shaft 5 is disposed on the ball bearings 4 and carries a bevel gear 6 in mesh with the bevel gear 7 at the end of the shaft of the motor 2. On both ends of the shaft 5 two crank pins 8 are provided which are staggered 180° and extend from the casing 3 on each side, a packing plate 9 being arranged on both sides.

The casing 3 contains further the two shafts 11 disposed on ball bearings, the points of exit of the shafts being protected by the packing plates 12, so that the casing 3 is well shut off and dust cannot enter into the gearing and motor. Each of the shafts 11 carries outside the casing 3 a rocker member 13 whose lower portions 14 are constructed so as to be able to receive steel shavings and brushes, and each member 13 is provided with a bolt 15 to which, on a ball bearing, a connecting rod 16 is articulated which with its other end is disposed on one of the crank pins 8 on a ball bearing. The jacket 1 has on one side the two bosses 17 accommodating a shaft 18 on which a roll 20, which does not contact with the floor during operation of the device, is arranged between the bosses. The jacket 1 is further provided with a clamp 21 adapted to hold the handle 19.

In the topmost portion of the jacket 1 a casing 22 for the propeller 23 is provided which rests on the shaft end of the motor 2 and draws the air out of the inside of the jacket 1. The casing 22 is in communication with a connection 24 to which a filtering bag can be attached.

On either side of the jacket 1 a container 25 for liquid floor polish is disposed, and a conduit leads from the container 25 to the polishing de-

vice 26 arranged between the two rocker members 13 and having in the center of its underside a nozzle 27 which can be shut off by the screw 28 when the polishing device is not in use. The handle 19 is a pump cylinder. The piston 29 can be moved by the handle 30, and a valve 31 serves for drawing in air which through a bore in the shaft 18 and a conduit 40 is passed up into the container 25. The rocker members 13 are provided with brushes for polishing, the consumption of polish being very economical, as the pump is actuated only when necessary.

The steel shavings are preferably inserted in special containers 32 secured to the rocker members 13. The containers 32 open downwardly and contain a plate 33 which is pressed against the opening by the springs 34. A rotatable bolt 35 passes through the containers 32 and projects over their two narrow sides. It carries a lever 36 disposed inside the containers and fitted with a nose 37, and supports on the outside of the containers two levers 38, the noses 37 serving for holding in position the plates 33 within the containers 32. In order to fill the containers 32 with steel shavings, the plate 33 is pressed inwardly and the levers 38 are turned up, the plates 33 being held in this position by the noses 37. The steel shavings can then be put in whereupon the containers 32 are secured to the rocker members 13. During the first motion of the rocker members 13 the levers 38 will strike a stop 39 on the jacket 1 and will be reversed whereby the noses 37 are caused to release the plate 33 which is pressed down by the springs 34 to advance the steel shavings.

When the motor 2 is started, the shaft 5 will be driven by the bevel gears 7 and 6 and the two crank pins 8, which are staggered 180° relative to one another, will move by means of the rods

40

16 the two rocker members 13 to and fro. The motions of the two rocker members 13 are accurately compensated to prevent the appearance of a transposing component in the machine which is merely slightly moved up and down periodically, and this movement, as stated, helps to remove the waste particles from the steel shavings. By means of the handle 19 the machine is moved over the floor to be worked at will. When not in use, the machine can be turned over and moved on the two rolls 20 after the handle 19 has been fixed in the clamp 21. To exchange steel shavings and brushes the machine is turned over completely so as to rest on the handle 19 and the rolls 20.

I claim:—

1. The combination, in a floor surfacing machine, of a container adapted to hold steel shavings against the floor and means to simultaneously reciprocate said container along the floor and to rock it about a horizontal axis.

2. In a floor surfacing machine having open bottom containers adapted to hold steel wool against the floor and mechanism to reciprocate said container along the floor, a plate in said containers, springs for pressing the said plate towards the open bottom of the said containers, rotatable bolts disposed on the sides of the said containers, reversible levers with noses positioned inside the said containers and on the said bolts to hold the said plate in pressed-in position, a fixed stop on the stationary portion of the machine, and levers disposed on the said bolts outside the said containers, the said levers striking the said stop during the motion of the rocker members to reverse the said levers inside the said containers and to release the said plate.
